Primary Examiner — Ricky Pham(74) *Attorney, Agent, or Firm* — Dykema Gossett PLLC(57) **CLAIM**

An ornamental design for a taco griddle, as shown and described.

DESCRIPTION

FIG. 1 is a perspective top view of a taco griddle according to my new and ornamental design,

FIG. 2 is a top plan view thereof,

FIG. 3 is a bottom plan view thereof,

FIG. 4 is an elevational side view thereof, the opposite side view being a mirror image; and,

FIG. 5 is an elevational end view thereof, the opposite end view being a mirror image.

The broken lines in FIGS. 1-5 represent features which are not part of the claimed taco griddle.
